Primary Examiner — Kelley Donnelly(74) *Attorney, Agent, or Firm* — Sterne, Kessler, Goldstein & Fox P.L.L.C.(57) **CLAIM**

The ornamental design for a display structure, as shown and described.

DESCRIPTION

FIG. 1 is a top front perspective view of an embodiment of a display structure showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof showing a broken-line environmental table in use with the display structure; and, FIG. 9 is a side view of the broken-line environmental table and display structure of FIG. 8.

The broken lines in the Figures show portions of the display structure and environment which form no part of the claimed design. The oblique lines in the Figures show transparency and not surface ornamentation.
